(57) **CLAIM**

The ornamental design for a cabinet pull, as shown and described.

DESCRIPTION

In a preferred embodiment, the nature of this product is a pull for a cabinet door.

FIG. 1 is a front, left, upper perspective view of a cabinet pull embodying my new design;

FIG. 2 is a top plan view thereof, the bottom plan view being a mirror image thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a front, left, upper perspective view of the cabinet pull shown in an alternate vertical position.

The broken line representations of mounting holes in FIG. 6 are for the purpose of illustration only, and form no part of the claimed design.
